UNITED STATES PATENT OFFICE.

HENRY A. DEKAY, OF JERSEY CITY, NEW JERSEY.

DESIGN FOR A HAT-BOX.

SPECIFICATION forming part of Design No. 31,402, dated August 15, 1899.

Application filed July 14, 1899. Serial No. 723,856. Term of patent 14 years.

To all whom it may concern:

Be it known that I, HENRY A. DEKAY, a citizen of the United States, residing at Jersey City, in the county of Hudson and State of New Jersey, have invented and produced a new and original Design for a Hat-Box, of which the following is a specification.

The invention relates to a new and original design; and it has for its object to provide a design for a lady's hat-box that shall be both useful and ornamental.

The essential feature of the design resides in a hat-box having a rectangular body portion provided with vertical sides having approximately triangular upper portions curving inward to the center of and forming the top of the box.

In the drawings, Figure 1 is a perspective view of a hat-box, showing my new and original design. Fig. 2 is a plan view. Fig. 3 is a vertical sectional view.

Referring to the drawings, 1 designates a hat-box provided with a rectangular body portion 2, composed of vertical sides having

approximately triangular extensions 3, curving inward at the upper edges of the box and extending to the center of the top. The upper portions of the sides are rounded at 4, where the extensions are curved inward, and the rounded portions present convex faces, as clearly illustrated in Figs. 1 and 3 of the accompanying drawings. The bottom 5 of the box is rectangular to conform to the configuration of the sides. The outer face of the top of the body or shell of the box, which is arched, as shown in Fig. 2, is convex and the inner face is concave.

What is claimed is—

The design for a hat-box, herein shown and described.

In testimony that I claim the foregoing as my own I have hereto affixed my signature in the presence of two witnesses.

HENRY A. DEKAY.
